US00D835440S

(12) **United States Design Patent** (10) Patent No.: **US D835,440 S**
(45) Date of Patent: **** Dec. 11, 2018**

(54) **DISPLAY STAND**

- (71) Applicant: **Apple Inc.**, Cupertino, CA (US)
(72) Inventors: **Charles A. Schwalbach**, Menlo Park, CA (US); **Sheng Yang**, Mountain View, CA (US); **Russell John Kaaihue Heirakuji**, Cupertino, CA (US); **Carly Lynn Marasco**, Los Gatos, CA (US); **Michael Gorman**, Dublin, CA (US)
(73) Assignee: **Apple Inc.**, Cupertino, CA (US)
(**) Term: **15 Years**
(21) Appl. No.: **29/641,661**
(22) Filed: **Mar. 23, 2018**

Related U.S. Application Data

- (63) Continuation of application No. 29/609,617, filed on Jul. 3, 2017, now Pat. No. Des. 813,576, which is a continuation of application No. 29/588,390, filed on Dec. 20, 2016, now Pat. No. Des. 791,521, which is a continuation of application No. 29/588,391, filed on Dec. 20, 2016, now Pat. No. Des. 792,133, which is a continuation of application No. 29/564,382, filed on May 12, 2016, now Pat. No. Des. 777,482, which is a continuation of application No. 29/564,382, filed on May 12, 2016, now Pat. No. Des. 777,482, which is a continuation of application No. 29/537,088, filed on Aug. 21, 2015, now Pat. No. Des. 756,152, which is a continuation of application No. 29/507,269, filed on Oct. 24, 2014, now Pat. No. Des. 737,081.

(57) **CLAIM**

The ornamental design for a display stand, as shown and described.

DESCRIPTION

FIG. 1 is a top front perspective view of a display stand showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines in the figures show portions of the display stand that form no part of the claimed design.

The dot-dash broken lines in the figures show boundaries that form no part of the claimed design.

1 Claim, 6 Drawing Sheets
